UNITED STATES PATENT OFFICE

JACOB FOBN, OF JAMESBURG, NEW JERSEY

TURFING MACHINE

Application filed February 11, 1932. Serial No. 592,409.

The present invention relates to new and useful improvements in turfing machines and has for its primary object to provide, in a manner as hereinafter set forth, a machine of 5 this character embodying a novel construction, combination and arrangement of parts whereby carpets of various dimensions may be rapidly turfed.

Another important object of the invention 10 is to provide a turfing machine embodying novel means for feeding the material beneath the turfing needles, a series of said needles being provided and mounted for vertical reciprocation.

Another important object of the invention 15 is to provide novel means for holding the material down during the withdrawal of the needles therefrom.

Other objects of the invention are to provide 20 a turfing machine of the character described which will be simple in construction, strong, durable, efficient and reliable in operation and which may be manufactured and maintained at low cost.

All of the foregoing and still further objects and advantages of the invention will become apparent from a study of the following specification, taken in connection with the 25 accompanying drawings wherein like characters of reference designate corresponding parts throughout the several views, and wherein:—

Figure 1 is a view in top plan of a turfing machine constructed in accordance with the 30 present invention.

Figure 2 is a view in vertical section through the machine, the arrows indicating the course of the material.

Figure 3 is a view in vertical section 35 through the upper portion of the machine showing the needles in their lowermost position and the hold down or foot retracted to inoperative position.

Figure 4 is a view in elevation of the upper portion of the machine looking at the side thereof which carries the feed roller actuating mechanism.

Figure 5 is a detail view in vertical section 40 showing the position of the needles when

about to enter the material with the foot about to be moved to retracted position.

Figure 6 is a detail view in vertical section 45 through one end portion of the machine showing the resilient means for anchoring the foot carriage and for actuating the same toward its operative position.

Figure 7 is a view in elevation of the upper portion of the machine looking at the opposite side thereof to that shown in Figure 4. 50

Figure 8 is a detail view showing the feed roller actuating and retaining pawls.

Figure 9 is a detail view in vertical section 55 taken substantially on the line 9—9 of Figure 4.

Figure 10 is a detail view in perspective of one of the foot actuating cams.

Figure 11 is a detail view in top plan of 60 an intermediate portion of the needle comb bar.

Figure 12 is a detail view in vertical section 65 through a portion of the vertically reciprocating needle bar with a needle in position therein.

Figure 13 is a detail view in vertical section 70 through the foot, the carriage for said foot and one of the adjustable resilient braces for the foot.

Referring now to the drawings in detail, 75 it will be seen that the reference numeral 1 designates generally a supporting structure having a front built to support an inclined panel 2. Rising from the top of the supporting structure 1 are the uprights 3 having bearings at their upper ends in which a shaft 4 is journalled. Disks 5 are fixed on the end portions of the shaft 4 outwardly of the uprights 3 for rotation with said shaft 4. The shaft 4 may be rotated by any suitable means.

An angle bar 6 extends between the uprights 3 and is connected thereto for vertical sliding movement through the medium of the eyes 7 on the ends of said angle bar. A needle bar 8 of angular cross section is secured to the bar 6. One side of the needle bar 7 projects forwardly from the bar 6 and is provided with a series of openings for the reception of the turfing needles 9 which are removably secured in position through the medium of set screws 10. Pitmen 11 have 80

one end pivotally connected off center to the outer sides of the disks 5 and their other ends pivotally connected to the eyes 7 for reciprocating the turfing needles 9 in a vertical plane when the machine is in operation.

- 5 A spur equipped feed roller 12 is journaled in bearings 13 on the front portion of the top of the supporting structure 1, one end portion of the shaft 14 of said feed roller projecting a distance beyond its bearing and having fixed thereon a ratchet gear 15. Rotatably connected to this end portion of the feed roller shaft 14 is one end of an actuating toggle 16 which has its other end pivotally connected by a pin and slot connection 17 to a substantially U-shaped bracket 18 which is mounted on the upper portion of the adjacent pitman 11. A spring pressed actuating pawl 19 is pivotally mounted on the lower portion of the toggle 16 and is operatively engaged with the ratchet gear 15, thus the feed roller 12 is operatively connected to the shaft 4 for actuation thereby. A spring actuated retaining pawl 20 is pivotally mounted on a support 21 which rises from the structure 1, said retaining pawl being operatively engageable with the ratchet gear 15.

Extending from the front to the rear of the upper portion of the supporting structure 1 are the spaced, parallel, horizontal bars 22 upon which a carriage 23 is mounted for horizontal sliding movement. Mounted on the carriage 23 and projecting beyond one side thereof is a presser foot 24 which is slightly angular in transverse section. This is illustrated to advantage in Figure 13 of the drawings. The ends of the presser foot 24 are fixed to the carriage 23. At intermediate points the presser foot 24 is braced against upward flexing by the bowed, resilient braces 25 having one end anchored to the presser foot and their other ends anchored to the carriage. The resilient braces 25 pass through the guides 26 which are mounted vertically on the carriage 23. Adjusting screws 27 are threaded through the upper ends of the guides 26 and engaged with the braces 25 for regulating the tension of said braces. A needle comb bar 28 extends across the upper portion of the supporting structure 1 beneath the needles 9 and is of angular cross section. As clearly seen in Figure 11 of the drawings, the slots of the comb 28 are enlarged at their ends, as at 29, to accommodate the needles. When in operative position, the projecting portion of the foot 24 is disposed above the comb 28.

Arms 30 are mounted on the end portions of the carriage 23 and project rearwardly beyond said carriage and have journaled on their free end portions the rollers 31. Cams 32 are mounted on the end portions of the bar 6 and depend therefrom for operative engagement with the rollers 31 when the needles move downwardly. The cams 32 are secured

to the bar 6 through the medium of bolts and are adjustable on said bar 6 by reason of the slots 33 provided in said cams.

A shaft 34 is journaled for rotation on the rear portion of the supporting structure 1 and has fixed thereon the material supporting roller 35 from which the spurs 36 project. As illustrated to advantage in Figure 1 of the drawings, one end portion of the shaft 34 projects beyond the supporting structure 1 and has fixed thereon a spool 37. The spool 37 is to have connected thereto for winding thereon a weight supporting tensioning cable or tape. The guide rod 38 is mounted on the upper rear portion of the supporting structure and a similar guide rod 39 is mounted on the supporting structure adjacent the rear of the comb 28. Another guide rod 40 is mounted on the supporting structure forwardly of the carriage 23 and directly beneath the feed roller 12.

In operation, the roll of material is mounted on the roller 35 and, as indicated by the arrows in Figure 2 of the drawings, is trained over the rods 38 and 39, between the comb 28 and the presser foot 24, beneath the carriage 23, then between the rod 40 and the feed roller 12 where it is operatively engaged by said feed roller and then passes beneath the adjacent upper portion of the supporting structure and extends down over the inclined panel 2. When the shaft 4 is rotated, the feed roller 12 is actuated in a manner to draw the material from the roller 35 in a step by step fashion beneath the needles 9. Also, when the shaft 4 is rotated, the needles 9 are reciprocated vertically and are driven through the material, said needles passing through the comb 28. While the needles are engaged in the material, said material is stationary. Just before the needles reach the material on the downward stroke, the cams 32 engage the rollers 31 and actuate the carriage 23 to withdraw the presser foot 24 from the path of the needles. The carriage 23 is yieldingly retained on the bars 22 by the coil springs 41 having one end anchored to said carriage and their other ends anchored to the supporting structure. Coil springs 42 also have one end connected to the carriage 23 and their other ends connected to the supporting structure, as best seen in Figure 6 of the drawings, and are arranged to yieldingly urge the carriage and the presser foot toward operative position. When the needles are about to be withdrawn from the material, the presser foot is in engagement with said material at a point closely adjacent the needles and immediately after the needles clear the material, the presser foot moves to its former position and prevents damage to the turfs which have just been formed.

It is believed that the many advantages of a turfing machine constructed in accordance with the present invention will be readily un-

derstood, and although the preferred embodiment of the invention is as illustrated and described, it is to be understood that changes in the details of construction and in the combination and arrangement of parts 5 may be resorted to which will fall within the scope of the invention as claimed.

What is claimed is:—

1. A turfing machine comprising a supporting structure, a needle bar mounted for vertical reciprocation on the supporting structure, a series of needles mounted on the needle bar, means for actuating the needle bar, means for feeding the material beneath the needle bar for operative engagement by the needles, a shiftable presser foot mounted on the supporting structure and engageable with the material beneath the needles, and means operatively connecting the presser foot 15 to the needle bar for actuation thereby in a manner to shift the presser foot from the needles on the operating stroke of the needles.

2. A turfing machine comprising a supporting structure, a needle bar mounted for vertical reciprocation on the supporting structure, a series of needles mounted on the needle bar, means for actuating the needle bar, means for feeding the material beneath the needle bar for operative engagement by the needles, a shiftable presser foot mounted on the supporting structure and engageable with the material beneath the needles, and means operatively connecting the presser foot 25 to the needle bar for actuation thereby in a manner to shift the presser foot from the needles on the operating stroke of the needles, and resilient means operatively connected with the presser foot for returning said presser foot to its former position on the retracting 30 stroke of the needles.

3. A turfing machine comprising a supporting structure, a needle bar mounted for vertical reciprocation on the supporting structure, a series of needles mounted on the needle bar, means for actuating the needle bar, means for feeding the material beneath the needle bar for engagement by the needles, a carriage slidably mounted on the supporting structure, a presser foot mounted on the carriage and engageable with the material beneath the needles.

4. A turfing machine comprising a supporting structure, a needle bar mounted for vertical reciprocation on the supporting structure, a series of needles mounted on the needle bar, means for actuating the needle bar, means for feeding the material beneath the needle bar for engagement by the needles, a carriage slidably mounted on the supporting structure, a presser foot mounted on the carriage and engageable with the material beneath the needles, and means operatively connecting the carriage to the needle bar for actuation thereby on the downward move-

ment of said needle bar for withdrawing the presser foot from beneath the needles.

5. A turfing machine comprising a supporting structure, a needle bar mounted for vertical reciprocation on the supporting structure, a series of needles mounted on the needle bar, means for actuating the needle bar, means for feeding the material beneath the needle bar for engagement by the needles, a carriage slidably mounted on the supporting structure, a presser foot mounted on the carriage and engageable with the material beneath the needles, and means operatively connecting the carriage to the needle bar for actuation thereby on the downward movement of said needle bar for withdrawing the presser foot from beneath the needles, the last named means including rollers mounted on the carriage, and cams mounted on the needle bar and operatively engageable with the rollers.

6. A turfing machine comprising a supporting structure, a series of needles mounted for vertical reciprocation on the supporting structure, means for actuating the needles, means for feeding the material beneath the needles for engagement by said needles, a carriage slidably mounted on the supporting structure, a presser foot mounted on the carriage and engageable with the material beneath the needles, means for actuating the carriage, resilient braces engaged with intermediate portions of the presser foot for retaining said presser foot against upward flexing, and means engaged with the braces for regulating the tension of said braces.

In testimony whereof I affix my signature.
JACOB FOBEN.
